UNITED STATES PATENT OFFICE.

JAMES E. PARKER, OF NEW YORK, N. Y.

TYPE-FORM.

1,187,085.

Specification of Letters Patent. Patented June 13, 1916.

Application filed October 30, 1914. Serial No. 869,457.

To all whom it may concern:

Be it known that I, JAMES E. PARKER, a citizen of the United States, residing at New York, in the county of New York and State of New York, have invented a new and useful Type-Form, of which the following is a specification.

The present invention relates to improvements in type forms, one object of the invention, being the provision of a novel apparatus and method, by means of which the various elements of the form, including the type, spaces, quads, leads, reglets, furniture and so forth, which have a tendency to "creep up" or fall out in the usual method of securing in chases, are so locked as to prevent such movement and to permit of the type, type form, or the chase to be moved about in security without the danger of the various elements thereof becoming loose and falling out.

It is a known fact that the spacing equipment in type of such forms, such as spacers, quads, leads, reglets, furniture and so forth, all have a tendency to creep up and so disfigure the copy being printed as to render the work undesirable and unfit for sending out. Also in the handling of type, it is extremely difficult to maintain the various types and spacing equipment in a permanent relative position to each other, causing loss of time and injury to the equipment by its spilling. The type and spacing equipment is supposed to be held in place by the locking up of the type and equipment in the chase or by binding or holding together thereof, so tightly that no movement can possibly take place. This is impossible if there is the slightest irregularity in the equipment. To overcome this tendency of the equipment creeping so far upwardly, as to spoil the copy and cause the loss of time and material, the present method has been devised and has proved practical where employed.

In this instance, the various elements constituting the form are preferably notched and thus provide, when properly assembled, a transverse slot or recess between the rows of type for introduction therebetween of a locking member whose ends may be of sufficient length to extend beyond the rows and engage the locking groove within the chase

or slot recess in the adjacent type, lines of type or equipment.

With this peculiar arrangement and construction of type, the compulsory use of special equipment is not necessary, it being necessary to provide a uniform notch or nick in all of the type and equipment which can be made while the type is being cast or the equipment is being made or afterward.

With the foregoing and other objects in view which will appear as the description appears, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a perspective view of a single type which is indicative of the other equipment constructed according to and embodying the present invention. Fig. 2 illustrates in perspective several rows of type set up. Fig. 3 represents several rows set up with the locking members in position. Fig. 4 is a similar view to Fig. 3 showing the type, reglets, quad and other spacing elements properly assembled. Fig. 5 is a perspective view showing the usual method of setting up leaded matter. Fig. 6 is a perspective view showing the method of setting up leaded matter according to the present invention. Fig. 7 is a perspective view of a novel form of lead used in conjunction with the present type form. Fig. 8 is a perspective view of another method of securing leaded matter in position. Fig. 9 is a perspective view of the chase with the upper locking plates removed. Fig. 10 is a perspective view of a portion of the chase showing some of the type in proper position therewithin. Fig. 11 is a detailed perspective view showing the relative position of the locking rods and leads in place.

The type 1 or other equipment is notched or nicked as at 2 and 3 upon both sides, this structure being clearly illustrated in Fig. 1.

When the type matter is "close set," each line of type is in close contact as shown in Fig. 2, so that the notches 2 and 3 are in

alinement, to receive the rod 4, as illustrated in Fig. 3 so that the adjacent lines of type are locked, the outer ends of the rod 4 being projected, if desired, beyond the respective rows so that such ends will be engaged with in the chase or with other type or equipment, as clearly illustrated in Figs. 10 and 11, and later to be described.

Where the lead 5 is used as shown in Figs. 5 and 6, it is necessary that the rod 4' be of slightly greater diameter than the rod 4 above set forth, so that the same will be properly positioned within the recesses or notches 2 and 3, and thus lock the lines of type, all spacing equipment therein, and the lead, against creeping upwardly. It has also been found desirable where the rod 4' may be dispensed with, that the lead 6 as illustrated in Fig. 7, may be provided with the lip 7, which in turn engages in the recess 2 of the line of type and thus locks the line against upward movement. Where this construction is employed, the lead or spacer 8 is disposed between certain of the lines of type so that the lugs 8' thereof, will project beyond the lines and engage either within the recesses 12 of the longitudinal members 10 and 10' of the chase, as particularly illustrated in Figs. 10 and 11, or within the slot 2 or 3 of the other type or equipment.

In setting up the present equipment, the various elements of the form as particularly illustrated in Fig. 4, are placed within the chase one line at a time toward the respective end 9 as clearly illustrated in Fig. 9, the rod 4 being placed within the respective recesses 12 formed in the longitudinal members 10 and 10' of the chase and held downwardly by means of the clamping or limiting plates 13 which are attached to the upper edges or faces of the respective longitudinal members 10 and 10'. Thus as each succeeding line of type is placed in position within the chase, the rods 4 or 4' and the leads 8 are placed in position so that the lines of type are thus locked within the chase and against upward movement, the members 9-9', 10 and 10' being securely held together so that the complete form may be moved with impunity and without any danger of the type creeping upwardly or of them becoming pied.

The lead 8 may be provided with a lip as 7 so as to engage within the respective notches 2 and 3 of the line of type and thus coöperate with the lugs 8' to assist in holding the type line downwardly within the chase member.

It will thus be seen that with the rods 4 or 60 middle leads 8 of slightly greater length than the lines of type within the form that the ends extend to rest within the notches or recesses of the chase and be held therein, so as to be locked against upward movement, 65 but yet are permitted the necessary longi-

tudinal movement to be placed into and out of position. It will thus be seen that the rods or middle leads coöperate with the notches of the type to lock the type against creeping movement, and that also the 70 notches of the type and other members of the form coöperate to lock the rods and middle leads against movement, thus all members coöperating to hold the type form in fixed relation and not depending upon the 75 clamping effect between the lines of type as is the usual practice.

By use of this method, the type matter need not to be locked up or bound up so tightly, and it is readily seen that any portion of the type matter with its spacing equipment can be readily lifted out of the chase or otherwise be handled without danger of spilling.

Corrections or alterations may be made 85 with the greatest ease, the condition of the character type and position of the rods are visible, and the spacing equipment is so notched as to render it impossible to injure any portion of the equipment by the inserting 90 of any equipment apparently correct, as all except the character type are notched so that it is immaterial whether they be inverted or reversed within the form, and it is evident that it would be impossible in view of accurate copy, to have the character type inverted or reversed or 95 in other than its proper position.

Where necessary to hold the type and matter in proper position, a rubber spacer 100 14 may be used, the same being compressed if necessary to bring the type in a perfectly upright position and thus preventing any lateral movement or tilting of the type in the lines which may be a little shorter than 105 the other.

When type-set matter is to be held set up for future use, the usual method of preserving the composition intact, is to remove the chase, and then to wind twine or cord 110 around the type matter as tightly as possible before placing in the place for storage, the handling of which gives ample opportunity to spill or pi the type matter. The present improvement is of value inasmuch as there 115 is no chance for any of the type or equipment to drop out when wrapped with the twine or cord, and the matter is transferred from one place to another. The improvement is also of value in the sale and shipment of new type, whereby the characters are held in such a firm position that the type may be wrapped, maintained and rehandled while subjected to the least chance of injury.

Although the locking member in the present instance has been shown as extended beyond the rows of type, to engage the locking grooves within the chase, it is not absolutely essential that the same should extend that far or where the lines are short or where a 120 125 130

line is placed at right angles to the other lines within the form, the ends of the locking members would then engage the nick 2 or 3 or either an adjacent type line of type, 5 or the furniture.

Although it has been stated that the nicks 2 and 3 can be placed upon the type when made, the same may be cut in bodies of type after the same have been made, it being only 10 essential that they be provided for the present manipulation of this system.

When the present type construction is used in a cylinder press in which the compression is given by a progressive action, it 15 has been found advisable, though not compulsory, to have a lead extending above the nick in the leaded line, or inverted also to guard the possibility of the type breaking off at its thin portion.

20 Instead of the type set matter being lifted into and out of the chase, it has been found necessary in some instances that the chase itself be lifted into and out of position from about the type set matter and in order to do 25 so, a chase as shown and heretofore described is capable of such operation although it may be operated as heretofore set forth.

In this form of chase, the side members 30 either 10 or 10', have been cut down flush with the lower edge of the locking groove 12 so as to permit of the withdrawal of the locking member 4 if necessary from the type matter within the chase. The locking plate 35 13 for this side is so constructed that when in place will preserve the longitudinal locking groove to receive or engage the ends of the projecting rods 4 or 4'. The locking plates are fastened upon the members 9 and 40 9' as well as upon the members 10 and 10' of the chase.

Another manner of setting up the type matter, consists in placing the elements as usual in a galley, line by line, the rods or 45 locking members being placed in position and the entire matter then lifted or slid off of the galley onto a table and then either lifted into the chase or else the chase placed about the type set matter, the clamping or 50 limiting plates being attached to the upper edge of the chase afterward, it being apparent that many methods of setting may be accomplished with the present system.

It will be noted that the spacing elements, 55 except the character type are each provided with two additional notches to permit

of the equipment being used in an inverted or reversed position, thus being well within the spirit of the present invention.

What is claimed is:

1. A type form embodying lines of type, locking members therebetween and engaged therewith to hold the type in position, and spacers between the lines of type behind and held in position by said locking members. 60 65

2. A type form embodying a chase having opposite recesses, lines of type within the chase, locking members between said lines of type and having their ends engaging in said recesses, the lines of type being engaged with 70 said members to prevent their displacement, and spacers between the lines of type behind and held in position by said locking members.

3. A type form embodying lines of type, 75 rods therebetween, each individual type having opposite notches receiving the respective rods, and spacers between the lines of type behind and held in place by said rods.

4. A type form embodying a chase having 80 opposite recesses, lines of type within the chase, rods between said lines of type and having their ends protruding and engaging in said recesses, each individual type having 85 opposite notches receiving the respective rods, and spacers between the lines of type behind said rods.

5. A type form embodying a chase having opposite recesses, lines of type within said 90 chase and having registering notches upon opposite sides, rods disposed between the lines of type to be received by the recesses and having their ends engageable in said recesses, and spacers disposed between the lines of type and having lugs engageable in 95 said recesses.

6. A type form, embodying lines of type having registering notches upon opposite sides, locking members disposable between the lines of type to be received by said 100 notches, and spacers disposable between the lines of type and having projecting terminal lugs, said lugs and terminals of the locking members being engageable with a support.

In testimony that I claim the foregoing as 105 my own, I have hereto affixed my signature in the presence of two witnesses.
